UNITED STATES PATENT OFFICE.

JOHN S. SKELLY, OF MONONGAHELA, PENNSYLVANIA, ASSIGNOR TO INTERNATIONAL COMBUSTION ENGINEERING CORPORATION, A CORPORATION OF DELAWARE.

UNDERFEED STOKER.

Application filed April 25, 1921. Serial No. 464,297.

To all whom it may concern:

Be it known that I, JOHN S. SKELLY, a citizen of the United States, and a resident of Monongahela, in the county of Washington and State of Pennsylvania, have made a new and useful Invention in Underfeed Stokers, of which the following is a specification.

This invention relates to furnaces and particularly to furnaces in which automatic means are employed for delivering fuel to the furnace and for propelling it across fuel-supporting elements thereof.

An object of my invention is to produce a furnace of the type specified in which improved means are employed for propelling fuel through the furnace and for effectively controlling combustion throughout the fuel bed.

A further object is to produce a furnace in which effective means are employed for controlling the depth and the contour of the fuel bed within the furnace.

These and other objects, which will be made more apparent throughout the further description, are attained by means of a furnace embodying the features herein described and illustrated in the drawings accompanying and forming a part hereof.

In the drawings, Figure 1 is a diagrammatic longitudinal sectional view of a furnace embodying my invention. Figure 2 is a fragmental sectional view illustrating a detail of construction employed in connection with the stoker, such as illustrated in Figure 1. Figure 3 is a view corresponding to Fig. 1, illustrating a modification of my invention, and Fig. 4 is a fragmentary plan view of the grate bars forming the fuel supporting surface.

The furnace or stoker illustrated is similar in its general construction and in its general principles of operation to the stoker illustrated and described in my application, Serial No. 398,897, filed July 26, 1920. It, however, embodies features which occasion a variation in its operation and cause it to differ structurally from the stoker illustrated in said application. As illustrated, it includes a retort 5 which extends transversely across the front of the furnace and to which fuel is fed by one or more mechanically-actuated plungers 6. The fuel fed by the plungers is received from one or

more hoppers 7 located at the front of the furnace. Where several plungers 6 are employed they may be spaced along the retort and may be operated by the same or by separate operating mechanisms. Fuel propelled into the retort from the hopper passes across a plate 8 which forms the floor of the retort and which is curved or inclined upwardly at its inner end, thereby forming the lower portion of the rear wall of the retort.

Fuel issuing from the retort traverses two series of grate bars in moving toward the rear end of the furnace. As illustrated, the first series of bars consists of alternately arranged moving bars 9 and stationary bars 9' located in parallel relation and extending from the retort downwardly toward the rear of the furnace. The forward ends 10 of these bars are so formed, and so located and arranged, that they, in effect, form a continuation of the upwardly curved portion of the retort floor 8 and, therefore, form the upper portion of the rear wall of the retort. The rear ends of these bars overlap the forward ends of the second series of bars.

The second series of bars consists of alternately-arranged moving bars 11 and stationary bars 11' located in parallel relation and inclined downwardly toward the rear end of the furnace. The inclination of these bars is preferably much less than that of the bars 9 and 9' and their rear ends discharge directly into the ash pit or well 12 which is located between them and the bridge wall 13 of the furnace.

The ash pit or well is preferably provided with a clinker crushing and ash moving mechanism such as the ordinary clinker grinding rolls or a screw conveyor for breaking up and discharging clinker and ash from the furnace.

As shown in the drawings, the plate 8 is mounted on and, in effect, forms a part of the framework of the stoker. The hopper 7 is so arranged that it feeds directly onto the forward end of this plate and the plunger 6, moving parallel to the adjacent portion of the plate, propels the fuel rearwardly across the plate and through the retort onto the grate bars. The fuel fed across the plate 8 traverses an expanding passage 14 as it enters the retort proper.

This passage is formed between the plate 8 and an upwardly and rearwardly inclined plate 15 which, as illustrated, forms a support for the upper portion of the front wall 5 of the stoker.

The vertical thickness of each plunger 6 is so proportioned with relation to the vertical width of the inlet end of the passage 14 as to avoid fuel packing. The increasing width of this passage also prevents fuel packing and insures the delivery of a more or less loose mass of fuel to the retort.

As shown in the drawings, the grate bars 9 and 9' are hollow, each grate bar being 15 provided with an air admission port 17 in its lower face and at its forward end and an air delivery port 18 in its lower face at its rear end. The grate bars are so mounted on the frame portion of the stoker that the 20 ports 17 register with and receive air under pressure from an air conduit 19. The rear ends of the bars 9 and 9' are so mounted and so located and arranged that the air ports 18 communicate with what may be 25 termed a secondary air chamber 20, which is located below the series of bars 9 and 9' and receives air from the passage 19 after it has passed through the hollow interior of the bars.

30 As previously stated, the forward ends of the bars 9 and 9' form a continuation of the upwardly-inclined or curved portion of the plate 8. This is accomplished by making the bars wedge-shaped at their 35 forward ends. For the purpose of delivering air in adequate quantities to the fuel as it issues from the retort and as it first moves onto the grate bars 9 and 9', I have provided those bars 40 with air delivery apertures 21 located in the nose or that portion of each bar which forms a continuation of the retort wall, and also in the forward end of the fuel supporting portion of each bar. The arrangement of the bars 11 and 11' shown 45 in Figure 1 is similar to that shown in my above-mentioned co-pending application.

Air under pressure is delivered to these bars through inlet ports 22 which register 50 with the upper end of a delivery conduit 23. These bars are also provided in their fuel supporting surfaces with air delivery apertures 24 which are located adjacent the forward ends of the bars. The lower face 55 of each bar is provided with an air delivery port 25 which discharges into a chamber 26 located below the series of bars. In this case, as in the case of the bars 20, the air so discharged is preheated in its 60 passage through the bars and then is delivered to the fuel bed through the spaces between the bars.

In my co-pending application I have described the means employed for imparting 65 a reciprocatory motion to the moving grate

bars of each series and I have also described in detail means employed for holding the stationary bars in place on the framework of the stoker. Figure 2 illustrates a modification of the means disclosed 70 in said application for holding the stationary bars 9' of the first series in place. As here shown, the framework of the stoker is provided with a stationary bar 27, the upper edge of which is engaged by downwardly-projecting lugs 28 formed on the lower face of each stationary bar. The lugs straddle the bar and in this way hold it stationary during the reciprocations of 75 the adjacent moving bars. 80

In Fig. 3, I have illustrated a modified form of stoker which is similar in general details to the structure illustrated in Fig. 1. The bars 11 and 11' of the second series are, however, so formed that they materially modify the distribution of fuel along the fuel-supporting surface and, consequently, the contour of the fuel bed. Broadly speaking, these grate bars are so arranged that the fuel traversing them does not move downwardly as it moves across their fuel-supporting surfaces. In the preferred form illustrated, the fuel-supporting surfaces of the bars 11 and 11' are inclined upwardly from the horizontal so that the fuel traversing them is actually elevated as it passes across them toward the ash pit or well 12. With this construction, the tendency of the fuel bed to thin out toward the rear of the furnace is materially decreased and, as a matter of fact, there is a tendency for the fuel bed to thicken at the point where the fuel issues from the bars 9 and 9' onto the bars 11 and 11' of the second series. 95 100 105

The air distribution in the stoker illustrated in Fig. 3 is similar to that of the stoker disclosed in Fig. 1. The bars of both series are each provided with air inlet and air discharge ports and air delivery 110 apertures as described in connection with Fig. 1.

The operation of the apparatus disclosed in Fig. 1 is briefly as follows: The reciprocation of the plungers 6 impels fuel from the hoppers 7 into the retort 5. It will, of course, be understood that the fuel is, in effect, crowded into the retort by oncoming fuel and in this way is delivered onto the grate bars 9 and 9'. The reciprocation of the moving grate bars 9 not only operates to break up the fuel bed supported by the bars and the mass of fuel issuing from the retort, but also operates to propel fuel 115 downwardly along the bars. The reciprocation of the moving bars 11 also propels the fuel rearwardly toward the well 12 and breaks up the portion of the fuel bed supported by them. The delivery of air to the fuel bed is substantially as described in my 120 125 130 135

co-pending application and, as there stated, is such as to maintain zones of increased combustion along the fuel bed.

The operation of the stoker shown in Fig. 5 is substantially similar to that just described except that the upward tilting of the grate bars 11 and 11' occasions a piling up of the fuel on these bars and consequently increases the average thickness of the fuel bed and varies its contour throughout the furnace.

15 While I have described but two embodiments of my invention, it will be apparent to those skilled in the art that various changes, modifications, additions and omissions may be made in the apparatus illustrated without departing from the spirit and scope of my invention, as set forth by the appended claims.

20 I claim as my invention:

1. In combination with a furnace, a stoker comprising a transversely extending retort located at the forward end of the furnace, a floor for the retort elevated at its rear or
25 fuel delivery edge, a series of spaced, downwardly inclined, alternately arranged, moving and stationary grate bars located in parallel relation and extending from the retort toward the rear of the furnace, each
30 bar having a wedge shaped forward end so arranged as to form an extension of the fuel delivery side of the retort and having apertures formed in the upper face thereof and in said wedge shaped forward
35 end, means for delivering air under pressure through said apertures and through the spaces between the bars, a second series of spaced, alternately arranged, moving and stationary grate bars located in parallel relation, overlapped at their forward ends by
40 said first series and extending toward the rear of the furnace at a materially different inclination from that of the bars of said first series, each bar of said second series
45 having apertures formed in the upper face near the forward end thereof and means for delivering air under pressure through said apertures and through the spaces between the bars of said second series.

50 2. In combination with a furnace, a stoker including a retort extending across the front of the furnace and provided with a substantially flat floor inclined upwardly at its rear or fuel delivery edge, a series of

spaced, downwardly inclined, alternately arranged, moving and stationary grate bars located in parallel relation and extending from said retort toward the rear of the furnace, each bar having a wedge shaped forward end so arranged as to form an extension of the fuel delivery side of the retort and having apertures formed in the upper face and in said wedge shaped forward end thereof, a second series of spaced, alternately arranged, moving and stationary grate bars located in parallel relation and overlapped by the rear ends of the bars of the first series and extending toward the rear of the furnace at a materially different inclination from the bars of the first series, each of said second series of bars having apertures formed in the upper face thereof and means for delivering air under pressure through said apertures and through the spaces between the bars. 75

3. In combination with a furnace, stoker including a retort extending across the front of the furnace and provided with a substantially flat floor inclined upwardly at its rear or fuel delivery edge, a series of 80 spaced, downwardly inclined, alternately arranged, moving and stationary grate bars located in parallel relation and extending from said retort toward the rear of the furnace, each bar having a wedge shaped forward end so arranged as to form an extension of the fuel delivery side of the retort and having apertures formed in the upper face and in said wedge shaped forward end thereof, a second series of 86 spaced, alternately arranged, moving and stationary grate bars located in parallel relation and extending toward the rear of the furnace at a materially different inclination from the bars of the first series, each of said second series of bars having apertures formed in the upper face thereof and means for delivering air under pressure through said apertures and through the spaces between the bars. 90 95 100

In testimony whereof, I have hereunto
subscribed my name this 20th day of April,
1921.

JOHN S. SKELLY.
